UNITED STATES PATENT OFFICE.

GEORGE A. PARKS, OF REVERE, MASSACHUSETTS.

LOCKING-BOLT FOR SHIPS' BERTHS.

SPECIFICATION forming part of Letters Patent No. 255,190, dated March 21, 1882.

Application filed July 6, 1881. (Model.)

To all whom it may concern:

Be it known that I, GEORGE A. PARKS, a citizen of the United States, residing at Revere, in the county of Suffolk and State of Massachusetts, have invented certain new and useful Improvements in Locking Devices for Ships' Berths; and I do hereby declare that the same are fully described in the following specification and illustrated in the accompanying drawings.

This invention relates to improvements in locking devices for self-leveling ship-berths, for the purpose of securing the berth firmly in position when not occupied. The invention, although particularly designed for locking ships' berths, is also equally useful as a locking device for any other desired purpose.

The invention is carried out as follows, reference being had to the accompanying drawings, on which Figure 1 represents a plan view of the device shown locked. Fig. 2 represents a sectional side elevation on the line A B, shown in Fig. 1. Fig. 3 represents a cross-section on the line C D, shown in Fig. 1; and Fig. 4 represents a cross-section on the line E F, shown in Fig. 2.

Similar letters refer to similar parts wherever they occur on the different parts of the drawings.

A represents a ship's berth or other object that is to be temporarily locked, and b represents a bulk-head or division-wall between a pair of ships' cabins.

To the inside of the berth a is secured the lock c, having spring-bolt d, spring e, tumblers f, key-hole g, and key h, as usual. In combination with the lock c and its spring-bolt d, I use a longitudinally-adjustable locking-bar i, provided with locking-notches i' and i'', as shown. The lock c is extended downward as a hollow projection, c', that serves as a bearing and guide for the adjustable notched locking-bar i in its forward-and-back motion. The outer end of the locking-bar i projects through a perforation in the end a' of the berth, as shown, as well as through a suitable metallic guide-plate, k, fastened to the inner end of the berth. The spring-bolt d, after being raised by its key h out of either of the notches i' or i'', on the locking-bar i, will allow of the sliding of the locking-bar i forward or back to a locked or unlocked position, as may be desired,

and in either of such positions the locking-bar i will be retained by the spring-bolt d, resting in either of the notches i' or i'', as shown.

The dotted lines in Figs. 1 and 2 represent the locking-bar i in an unlocked position—that is, the berth a is then liberated from the bulk-head or division-wall b. To the latter is secured the striker-plate l, having slotted opening l', in which the perforated striker m is adjustable up and down, and when so adjusted to correspond with the height of the locking-bar i said striker m is firmly secured in position by means of the set-screws n n', screwed through the upper and lower ends of the striker-plate l, as shown in Figs. 2 and 3. Such adjustment of the striker m is important to compensate for variations in a vertical direction of the ship's berth a.

The full lines in Figs. 1 and 2 show the end of the locking-bar i as locked and resting within the striker m. To unlock said bar i it is only necessary to raise the spring-bolt d, by means of the key h, out of the notch i'', when the locking-bar i is released from the lock c, and may be moved toward the left until the notch i' comes opposite to the spring-bolt d, when the latter is automatically forced by its spring e into the notch i', thus keeping the locking-bar i in an unlocked position from its striker until the bolt d is again raised by the key, allowing the bar i to be moved toward the right till its outer end enters the striker m at the same time as the spring-bolt d descends into the notch i'' on the locking-bar i.

In ships' berths I use one of these locking devices in each end of the berth; but for other purposes one single lock and locking-bar may be sufficient.

What I wish to secure by Letters Patent, and claim, is—

In combination, the lock c, its spring-bolt d, the adjustable notched locking-bar i i' i'', the striker-plate l, its adjustable striker m, and regulating-screws n n', as and for the purpose described.

In testimony whereof I have affixed my signature in presence of two witnesses.

GEORGE A. PARKS.
